LOCKING STUD AND SOCKET SNAP
FASTENER

Leo Roseman, Newark, N. J.

Application May 7, 1937, Serial No. 141,192

12 Claims. (Cl. 2-265)

This invention relates in general to snap fasteners of the head and socket type, and particularly to such fasteners especially adapted for use on garments such as corsets, brassières, shirts, 5 leggings, and surgical stockings, or on other articles such as garment bags, draperies and the like.

The present invention is related to that shown and claimed in my copending application, Serial 10 No. 106,326, filed October 19, 1936, wherein the complementary fastener elements are connectible in the general planes of the garment or article edges in a single movement in directions approximately perpendicular to said edges with the 15 edges in approximately abutting relation, and the complementary fastener elements are positively locked against accidental disconnection. The fastener disclosed in that application also permits disconnection of all complementary fastener 20 elements quickly at one time and in one simple continuous movement or pulling apart of the edge portions of the garment or article from one end toward the other in directions at angles to the general planes of said edge portions similar 25 to the movement incident to ripping or tearing of textile fabric.

The fastener disclosed in the above-mentioned copending application includes a stud element secured on one edge portion of the garment or 30 article and a socket element secured on the other edge portion, the stud element being provided with a shank having a head formed with a lateral shoulder or projection, and the socket element is approximately flat, comprising a single 35 piece of spring sheet metal folded upon itself to form a pair of opposite spring jaws movable apart in a direction approximately perpendicular to the plane of the respective garment edge portion and one jaw formed with a recess or opening 40 to receive and interlock with said shoulder of the stud element when the latter is inserted between the jaws. Also the fastener elements are secured between plies of fabric stitched together with gaps between them, the opening between 45 the jaws of each socket element facing outwardly through one gap in the corresponding edge portion to receive the shank of a stud element which projects from the other edge portion.

One object of the present invention is to provide 50 a fastener of the general character described wherein the socket element shall embody novel and improved features of construction for accurately guiding the head of the head of the stud element through the gap between the plies of fabric and into said opening in the socket ele-

ment, whereby the socket element shall be invisible and the gap shall be held open even after laundering of the fabric and difficulty in properly engaging the stud element with the socket element shall be reduced to the minimum.

Another object is to provide a socket element 5 of this character which shall have a novel and improved guide for the head of the stud element that shall also serve to reinforce the socket element, and shall permit the element to be made 10 thin and with a maximum of spring strength to effectually resist accidental disengagement of the stud element from the socket elements under strains incident to use of the fastener.

A further object is to provide in a fastener of 15 this character, a socket element having novel and improved means to cooperate with stitches for securing the socket element between plies of fabric and positively hold the socket element against turning and against displacement in 20 such a manner as to throw the stud receiving opening out of alignment with the gap between the plies, and to hold the fabric flat and unwrinkled over the socket element; and thus to provide in such a socket element laterally projecting lugs to be traversed by stitches, whereby 25 the element can be firmly secured between the fabric plies with a continuous straight line of stitches.

Another object is to provide such a socket element having the free edges of the jaws so formed 30 as to prevent catching or snagging of said edges in the fabric plies and thereby ensure free movement of the jaws between the plies, and to cause the jaws to be forced together with a wedge action 35 between the fabric plies to tightly grip the stud element under forces applied to the socket element while the latter is connected to a stud element and the fastener is in use.

A further object is to provide in a fastener of 40 the character described a novel and improved stud element so constructed as to conform to the curvature or angularity of the part over which the fastener is applied, for example, the curves 45 of the body where the fastener is on a garment, or the angular corners of a piece of furniture where the fastener is used in a furniture cover, whereby to ensure a smooth, close joint between the connected edges of the garment or article 50 and to reduce the application of strains to the fastener which might accidentally disconnect the complementary socket and stud elements.

Other objects, advantages and results will appear from the following description when read in 55

conjunction with the accompanying drawings in which

Figure 1 is a composite plan view of the complementary socket element and stud element parts 5 of the fastener in separated condition, portions of the fabric being broken away for clearness in illustration.

Figure 29 is a similar view of the stud element 70 shown in Figures 20 and 21, and

Figure 30 is a view similar to Figure 16 showing a modification of the socket element.

The invention contemplates the attachment of 75 the complementary stud elements and socket ele-

ments directly to the edges of a garment or other article to be connected or the attachment of the socket elements and stud elements to fabric tapes which are in turn secured to the edges. Referring to Figures 1 to 13 inclusive, the reference 5 characters A and B designate the edge portions of a garment or article to be connected, or a fabric tape, said edge portions having secured thereto respectively socket elements 1 and stud elements 2. As shown, the fastener elements are secured between the undersides of the garment edge portions or fabric strips A and B and other fabric strips 3, whereby the fastener elements are disposed between plies of fabric.

Each socket element includes a single piece of 15 spring sheet material folded upon itself as at 4 to form an approximately rectangular flat base having two opposed jaws 5 and 6 one of which has an opening or recess 7 adjacent the free front edge of the jaw and intermediate its width, while 20 the other jaw has a transverse groove or channel 8 comprising a corrugation which extends inwardly from the free edge of said jaw beyond the opening, recess or catch 7 in the other jaw to receive and guide the head of the complementary 25 stud element into the recess or opening 7. This corrugation 8 also reinforces the jaw 6 against flexing between its free edge and its juncture with the other jaw 5, so as to ensure the spring 30 action of the jaws occurring at the juncture 4 of the jaws and thereby provide maximum spring strength to effectually resist accidental disengagement of the stud element from the socket element under strains incident to use of the fastener. Also the corrugation with the groove 35 facing the other jaw provides a clearance or space for the stud element so that the main portions of the jaws may be arranged close together and thereby make the socket element of minimum thickness.

Preferably one jaw 6 is narrower than the other; in other words, the ends of the jaw 6 terminate short of the ends of the jaw 5 as shown in Figure 17, as described and claimed in my co-pending application Serial No. 113,815. 45 Also, at least one jaw, in the present instance the jaw 5 has a pair of lugs 9 projecting from the rear edge of the jaw in a common plane therewith, and if desired both ends of the jaw may have lugs as shown in Figure 30 where 50 lugs 10 are shown at the front end of the jaw 5 for the purpose about to be described.

It is also desirable that the portions of the front edges of the jaw 6 at opposite sides of the corrugation 8 recede longitudinally as at 11.

The socket elements are secured on the edges of the garment, tape or other article, preferably in equidistantly spaced relation longitudinally of said edges, with the openings between the jaws facing toward the edges and through openings 60 or gaps between the plies of material. A line of stitches 12 runs longitudinally of said edge of the piece of material adjacent or in abutting relation to the front free edges of the jaws of the socket elements and penetrates the plies of the piece at 65 opposite sides of the socket elements, said line of stitches preferably including superposed reinforcing stitches 13 at opposite sides of the groove or corrugation 8 of each socket element so as to leave a gap or opening 14 between the plies of the 70 pieces in alignment with said groove 8 to receive the head of the complementary stud element. These stitches draw the plies of material tightly over the free front edges of the socket elements and the corrugation 8 maintains the gap in open 75

condition even after laundering of the fabric material so as to constantly ensure a free opening for the insertion of the head of the stud element.

Another line of stitches 15 runs longitudinally of the piece of material adjacent or in abutting relation to the rear end of each socket element and includes tying stitches 16 passing through the plies of material and traversing the lugs 9. In this way, the socket elements are firmly secured in position between the plies of material against turning over and against sliding such as would throw the guide grooves 8 out of alignment with the corresponding gaps 14. Where the socket element has the lugs 10 at the free front edge 15 of one jaw, the reenforcing stitches 13 traverse the lugs 10, and these lugs serve both to firmly secure the socket element against sliding or turning between the plies and also hold taut the material of the plies at opposite sides of the gap 14 so as to prevent loosening or buckling of the material of the plies at the gap in such a manner as to allow the stud element to enter between the socket element and the plies.

Due to the jaws 6 being narrower than the jaw 5 and also due to the lugs 9 in a common plane with the jaw 5, when the socket element is stitched between the plies of fabric the plies are drawn about the socket element as shown in Figures 5, 12, and 13 so that the plies overlying the wider jaw 5 are smooth and the socket element does not form a bulge or protuberance in the face ply; substantially the entire bulge resulting from the fastener element is formed in the plies overlying the narrower jaw 6.

Each of the stud elements 2 in includes a substantially flat base 17 formed of suitable material and having a shank 20 projecting from one edge thereof having flat sides 21 and a rounded head 22 with a shoulder 23 projecting approximately 40 perpendicularly to the plane of the flat sides 21, said shoulder merging into the edges 24 of the shank. Also, the base 17 preferably has beveled edges 18 for the same reason that the jaw 6 of the socket element is narrower than the jaw 5.

The bases of the stud elements are secured between the plies of the corresponding garment edge or tape in any suitable manner, for example in the same manner as the socket elements are secured, the shanks of the stud elements projecting from the edge of the corresponding piece of material as clearly shown in Figures 1 and 4.

Each stud element is complementary to one socket element and in connecting the complementary stud elements and socket elements, the edges of the respective pieces of material are moved edgewise toward each other so as to insert the heads of the stud elements between the jaws and in the grooves 8 of the corresponding socket elements, the jaws being sprung apart as said heads are inserted and then snapping over the shoulders 23 to cause interlocking engagement of the edges of the openings or catches 7 with the respective shoulders 23. Due to the relative narrowness of the jaw 6 and the receding front edges 11 of said jaw, the spring action of the jaws is free and unobstructed by frictional engagement of the front edges of the jaws with the fabric. The stud elements and socket elements are thereby positively interlocked with each other and will effectually withstand all strains tending to pull the edges apart in their own planes which is especially important in tight-fitting garments, such as corsets. The guide grooves 8 effectually guide the heads of the stud elements into the openings 7 and ensure that said heads shall be

properly engaged with the corresponding openings without danger of the heads being inserted between the jaws and the respective plies of material or inserted between the jaws out of alignment with the respective openings 7.

Preferably the shanks 20 of the stud elements will be disposed at angles to the planes of the respective bases 17 so that the socket element and stud element parts of the fastener may accurately conform to the curvature or angular formation 10 of the surface with which the fastener contacts when in use, for example the curves of the body or the corners of a piece of furniture. For example, in Figures 1 to 6 inclusive the shanks of the stud elements are so disposed as to conform 15 to curves of the body as when the fastener is used in a corset, while in Figures 20 and 21 the shanks of the stud elements are approximately perpendicular to the corresponding bases so that the two complementary parts C and D of the fastener may be disposed perpendicularly to each other as in a corner joint of a furniture cover. In Figures 1 to 6 inclusive the stud elements are shaped to conform to a convex curve, but the elements may also be shaped to conform to a concave curve as shown in Figure 19. The shape of the stud elements as described has the further advantage in preventing such relative tilting of the fastener elements as would pry open or excessively spread the jaws of the socket elements 20 under strains when the fastener is in use on curved or angular surfaces. Moreover, the structure ensures a smooth joint between the two parts of the fastener.

The receding portions 11 of the edges of the jaws 6 permit the fabric to be more snugly drawn about the corrugation 8 and accurately shape the gap to receive the stud. For the purpose of preventing cutting of the fabric or stitches the free edge of the jaw 6 which is parallel to the edge of the piece of material is preferably returned upon itself as at 25. This structure has an additional important function as described and claimed in my co-pending application Serial No. 113,815 in that when the complementary fastener elements 40 are connected together and the fastener is in use, the forces applied to the socket elements tending to separate the edges of the pieces of material will draw the free edges of the jaws 5 and 6 of the fastener elements with a wedge action into 50 engagement with the plies of fabric between which the socket elements are mounted, so as to tightly force the jaws into interlocking relation with the corresponding stud elements.

The complementary socket elements and stud elements may be separated in a continuous operation by oppositely directed forces on the edges of the pieces of material from one end toward the other in directions at angles to the planes of said edges so as to rotate the socket elements relatively to the stud elements about axes parallel to the general planes of the pieces or the axes of the shanks of the stud elements and remove the shoulders 23 of the stud elements out of the recesses 7 of the corresponding socket elements as 60 shown in Figures 4 to 6 inclusive. Figure 4 shows the stud element connected to the socket element while Figures 5 and 6 show the stud element rotated to move the shoulder 23 out of the opening 7. This relative movement of the edges of the pieces of material is similar to that of ripping fabric or a seam and permits easy and rapid disconnection of the edges of the pieces. This is especially desirable in tight fitting garments such as corsets, because only one edge need be pulled, 70 75

the other edge being held stationary by the body. The separation of the fastener elements is further facilitated by the spring frictional engagement of the jaws with the tapered sides 24 of the stud shanks which tends to eject the studs from the socket elements after the shoulders 23 of the heads have been rotated out of the openings 7 as shown in Figure 5.

The fastener elements when connected are held 10 against rotation by the edge portions of the pieces of material and the engagement of the jaws 5 and 6 with the flat sides 21 of the stud shanks.

If desired, the fastener elements may be separated from each other by a relative tilting or 15 hinge-like action which spreads the jaws apart to release the head of the stud element from the catch 7 of the socket element.

With the invention, it will be observed that when the fastener elements are connected all 20 metal is concealed and the edge portions of the two pieces of material may be brought into tight abutting relation so as to avoid the necessity for an underlying flap with its disadvantages and annoyances.

25 Moreover, the edge portions of the pieces of material when they are connected have their outer sides or faces smooth and free from bulges and in substantially the same plane or flush with each other so as to reduce the visibility of the 30 joint between the edges.

Instead of forming the jaw of the socket element with an opening or recess 7, the jaw may have a tooth, lug or catch 26 stamped therefrom to engage the shoulder 23 of the stud element as 35 shown in Figures 22 to 24 inclusive.

Moreover, if desired the lug or catch to engage the stud element might be formed in the jaw 6 as indicated at 27 in Figures 25 to 27 inclusive.

40 It will be understood by those skilled in the art that the foregoing illustrates the now preferred embodiment of the invention but that many modifications and changes may be made in the details of construction of the socket element and stud element and their connection to the 45 pieces of material without departing from the spirit or scope of the invention.

Having thus described my invention, what I claim is:

1. In a fastener, the combination of two pieces 50 of pliable material disposed in edgewise relation and each comprising a plurality of plies with an opening between them at their edges, a stud element secured between the plies of one of said pieces with a head projecting from said opening 55 in the edge of the piece between the plies thereof, an approximately flat socket element secured between the plies of the other piece and having opposed spring jaws with their free front edges disposed at the opening between said plies to 60 receive the head of said stud element between them, one of said jaws having a catch to receive and interlock with said head of the stud element and the other jaw having a guide channel facing the first jaw and leading inwardly from the free 65 edge of the jaw and said opening between the plies to said catch for guiding the head of said stud element into said catch.

2. The fastener set forth in claim 1 wherein 70 said socket element is formed of a sheet of spring metal folded upon itself to form the opposed jaws, and said guide channel comprises a corrugation in said jaw which reenforces the jaw against flexing between its free end and its juncture with the other jaw.

75 3. The fastener set forth in claim 1 wherein

said socket element is formed of a sheet of spring metal folded upon itself to form the opposed jaws, 10 said jaws are approximately of the same length, said groove comprises a corrugation in said jaw, and the free edge of said jaw recedes longitudinally thereof from and at opposite sides of said corrugation and from said edge of the corresponding piece of material while the free edge of the other jaw is approximately parallel to said edge of the piece.

4. In a fastener, a piece of pliable material comprising a plurality of plies having one edge of one ply secured to the other with a gap between the plies, an approximately flat socket element secured between said plies and having opposed 15 spring jaws with their free front edges disposed at said gap to receive the head of a complementary stud element between them, one of said jaws having a catch to receive and interlock with the head of the stud element, stitches passing through 20 said plies close to the front and the rear edges of said socket element, a plurality of lugs on said socket element, and other stitches passing through said plies and traversing said lugs.

5. The fastener set forth in claim 4 wherein 25 said lugs project from the edges of one of said jaws in a common plane therewith.

6. The fastener set forth in claim 4 wherein the end edges of one jaw terminate short of the end edges of the other jaw and said lugs project 30 from the rear edge of said second mentioned jaw in a common plane therewith outwardly of the end edges of the first mentioned jaw.

7. In a fastener, the combination of two pieces 35 of pliable material, each comprising a plurality of plies with an opening between them at their edges, a stud element comprising an approximately flat base secured between the plies of one of said pieces and having a shank with a head projecting from one edge of the base and 40 through said opening in the edge of said piece at an angle to the plane of the base and said piece, and an approximately flat spring socket element secured between the plies of the other piece with spring jaws having their free edges disposed at said opening in the corresponding 45 piece to receive said head and shank of the stud element between them, one of said jaws having a catch to receive and interlock with said head of the stud element.

8. The fastener set forth in claim 1 wherein 50 said guide channel comprises a corrugation in said jaw which reenforces the jaw against flexing between its free end and its juncture with the other jaw.

9. In a fastener, a piece of pliable material comprising a plurality of plies, means securing 55 said plies together at spaced points adjacent one edge of at least one ply to form a gap between said plies at said edge, an approximately flat socket element secured between the plies of said piece and having opposed spring jaws with their free edges disposed at said gap to receive a complementary stud element between them, one of said jaws having a catch to receive and interlock 60 with said complementary stud element and one jaw having a corrugation forming a groove on the side of the jaw facing the other jaw and leading inwardly from the free edge of the jaw and said gap to said catch, said corrugation 65 forming a rib on the other side of said jaw, whereby the free edges of said jaws and said corrugation hold said plies apart at said gap to maintain the gap freely open to receive said complementary stud element.

10. In a fastener, a piece of pliable material comprising a plurality of plies having one edge of one ply secured to the other with a gap between the plies, an approximately flat socket element secured between said plies and having opposed spring jaws with their free front edges disposed at said gap to receive the head of a complemental stud element between them, one of said jaws having a catch to receive and interlocking said head of the stud element, said socket element having a plurality of lugs projecting from the free front edge of at least one jaw at opposite sides of said gap between said plies, and stitches passing through the plies 10 of said piece of material and traversing said lugs, whereby to hold taut the plies at opposite sides of said gap and prevent lateral displacement of said socket element out of alinement with said gap.
11. In a fastener, a piece of pliable material comprising a plurality of plies having one edge of one ply secured to the other with a gap between the plies, an approximately flat socket element secured between said plies and having opposed spring jaws with their free front edges disposed at said gap to receive the head of a complemental stud element between them, one of said jaws having a catch to receive and interlock with said head of the stud element, said socket element having lugs projecting from the free front edges of one jaw at opposite sides of said gap and having other lugs projecting from other edges of the element, and means securing said socket element between said plies including stitches passing through said plies and traversing said lugs. 5
12. In a fastener, a piece of pliable material comprising a plurality of plies, means securing said plies together adjacent one edge of at least one ply to form a gap between said plies, and a flat spring socket element having a spring socket 15 to receive and interlock with a complemental stud element, said socket element being secured wholly between said plies with the mouth of said socket adjacent and opening through said gap, the edges of said socket element at its mouth 20 abutting said plies at the sides and ends of said gap to hold the plies apart at said gap and maintain the gap freely open to receive said stud element. 10

LEO ROSEMAN. 25
